UNITED STATES PATENT OFFICE.

HORACE S. GORDON, OF DAYTON, OHIO.

FOOD-GUARD.

967,366.

Specification of Letters Patent. Patented Aug. 16, 1910.

Application filed November 22, 1909. Serial No. 529,217.

To all whom it may concern:

Be it known that I, HORACE S. GORDON, a citizen of the United States, residing at Dayton, in the county of Montgomery and State of Ohio, have invented certain new and useful Improvements in Food-Guards; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in guards adapted for use on store counters and the like, and is adapted to prevent customers or other persons handling or fingering articles offered for sale, such as meat, or other foods which are exposed to view on counters in stores and markets.

The object of the invention is to provide a device of this type which is cheaply constructed, which allows the articles on a counter to be exposed to view, at the same time preventing persons handling the same, and which may be easily placed in a lowered position to allow the counter to be cleansed.

In the accompanying drawings, Figure 1 is a perspective view of the device attached to a counter and showing in broken lines, the position of the device when in a lowered position. Fig. 2 is an end elevation thereof.

Throughout the specification and drawings similar reference characters indicate corresponding parts.

Referring to the drawings, 1 indicates a counter of any construction upon the outer edges of which are mounted a suitable number of bearings 2 through which passes a rod 3. At the ends of the rod 3, are mounted upright rods 4 which are pivotally attached at their upper ends to a rod 5 which extends parallel with the rod 3. The ends of the rod 5 are bent at right angles as at 6, and the ends of the angular portions 6 are attached to a rod 7 which is parallel with the rods 5 and 3. The vertical and horizontal spaces thus formed by the rods 3, 4, 5, 6 and 7 are occupied by cross wires 8 forming meshes through which persons may view the articles on the counter, but which prevent such articles from being handled.

It will be understood that the device may be

of any size and length and that ordinarily it will extend the full length of a counter. The extreme outer ends of the rods 3, which may be separate attached portions, are bent at right angles and extend obliquely as at 9, 60 and are provided with eyes 10 which engage the extended ends 11 of the rod 7. The angular portions 9 form a brace to maintain the vertical mesh portion of the guard, and the horizontal mesh portion at approximately right angles when the guard is in position on the counter. When in this position the guard is prevented from rotating in the bearings 2, by braces 12 which stand upright and rest upon the counter and which are attached at their upper ends to the rod 7. When it is desired to cleanse the counter, the extensions 9 are sprung outwardly and the eyes 10 are released from the ends of the rod 7, thereby allowing the device to be dropped or placed in the position shown in dotted lines in Fig. 1, which leaves the counter unobstructed.

I claim:

1. In a guard of the type specified, a vertical mesh portion pivotally connected to a counter, a horizontal mesh portion pivotally connected to said vertical portion, a brace adapted to hold said vertical and horizontal portions at substantially right angles, and a brace mounted on the free edge of said horizontal portion and adapted to support said vertical and horizontal portions.

2. In a guard for the purposes specified, a vertical mesh portion having upper and lower horizontal rods and end vertical rods, a horizontal portion pivoted to said vertical portion and having an outer horizontal rod and end rods, said lower horizontal rod of the vertical mesh portion being extended at right angles and adapted to engage the outer horizontal rod of said horizontal portion whereby said vertical and horizontal portions are held substantially at right angles, braces attached to the said outer horizontal rod and adapted to support the vertical and horizontal portions, and pivot pieces for attaching the lower end of the vertical mesh portion to a counter.

In testimony whereof I affix my signature, in presence of two witnesses.

HORACE S. GORDON.
